The invention concerns the analysis of moving fluids which may be slurries or the like. According to the invention the fluid to be analysed flows under pressure through an orifice at such a rate that it forms a clearly defined jet. Thus non-contact means such as an X-ray device can be used to analyse the fluid without the need of a window between the analysis means and the fluid. Means are provided both for determining the flow rate of the fluid in the jet and its dimensions so that the non-contact analysis means can be protected from damage should the flow rate or the dimensions of the jet vary beyond predetermined limits.

Fig. 3

ANALYSIS OF MOVING FLUIDS

This is a continuation-in-part application of U.S. application Ser. No. 292,786, filed Sept. 27, 1972, now abandoned.

The present invention concerns the determination of elements in flowing systems.

This is frequently done by x-rays fluorescence and is particularly important in the analysis of mineral slurries. Thus radioisotope x-ray fluorescence analysis has been successfully applied to the on-stream determination in slurries of a number of elements such as calcium, zinc and tin. In known x-ray fluorescence systems for mineral slurries an x-ray transparent window is located between the flowing sample and the x-ray system. One main function of the window is to produce a relatively flat sample surface at a constant distance from the x-ray system. This is in fact essential for quantitative analysis. Another function is to protect the x-ray from the fluid.

However, such known systems have considerable disadvantages. The window, which must be very thin to allow the transmission of very low energy characteristic x-rays, is subject to abrasion, deposition, chemical attack, non-elastic deformation and degradation under high x-ray intensities. Furthermore, even when the window is as thin as abrasion and pressure variations permit, it strongly absorbs the characteristic x-rays from lighter elements such as aluminium, making their determination in flowing fluids difficult or impossible by x-ray fluorescence. However, in British patent specification No. 1,232,581, which is concerned with measuring the purity of fuel oil, a method of contactless analysis of oil is disclosed in which a jet of oil is passed through ultraviolet radiation and any subsequent fluorescence is detected so that impurities can be measured without actual contact being made. Nevertheless, the handling of fuel oil is a substantially easier undertaking than the mineral slurries with which the present invention is concerned. In particular the greater mass corrosiveness and the particulate nature of the mineral slurries means that should the stream of slurry spread beyond its intended boundaries during analysis considerable damage could be caused to the detection equipment.

The present invention has for an object to substantially reduce the possibility of such expensive damage occurring.

Three embodiments will now be described by way of example and with reference to the accompanying drawings in which:

FIG. 1 is a section through one embodiment of an x-ray fluorescent system constructed in accordance with the present invention;

FIG. 2 is a similar view of a second embodiment also constructed in accordance with the present invention, and

FIG. 3 shows a third embodiment.

In the Figures of the accompanying drawings, like integers will be designated by like reference numerals. FIG. 1 of the accompanying drawings shows an x-ray fluorescence analysis system in which fluid 1 flows vertically down through a pipe 2 having an orifice 3 of reduced cross-sectional area. The fluid 1 is pumped by a suitable pump having a smooth rate of delivery or fed from a constant head tank. The orifice 3 is smoothly contoured and in cross section is in the shape of an

elongated ellipse. The pipe 2 is made of any suitable material such as polythene and the orifice itself is made from a suitably wear resistant material such as neoprene or silicon carbide. An x-ray system 4 is mounted as close as possible to the orifice 3. The reason for this is that the surface of the jet of fluid is subject to large random and non-random variations in its position as the distance from the orifice 3 is increased. A non-dispersive x-ray system 4 has an x-ray source 5 and an associated detector 6 which gives an output on an output line 7 to a standard nucleonic measuring system which is not shown. The non-dispersive x-ray system 4 is conventional in nature. An on-stream energy dispersive analyser for x-ray fluorescence is described in the article by K.G.Carr-Brion in X-ray Spectrometry 2, 1973. In order to protect the x-ray system 4 from splashes when the rate of flow of the fluid is insufficient to form a clearly defined jet, a pressure or flow sensor 8 is provided on the pipe 2 a suitable distance upstream from the orifice 3. This sensor 8 controls an actuator 9 which in turn controls a shutter 10 which protects the face of the x-ray system 4 and which is moved away by the actuator 9 only when the sensor 8 gives an output signal indicating that the fluid pressure is sufficiently high and has been so for a preselected delay time.

In addition to measurement of the rate of flow of the fluid to be analysed means are also provided to detect if the dimensions of the stream passing the analytic equipment vary beyond predetermined limits. Such variation might be caused by an obstruction or a sudden change in the shape of the orifice 3 caused by a breakage.

Thus instability of the jet stream is detected by a pair of photo-electric sensors 20, 21. A light source 22 illuminates an edge of the jet and casts a shadow in the plane containing the photoelectric sensors 20, 21 so that should the width of the jet be correct in the plane of the sensors the edge of the shadow lies between the two sensors. The outputs of sensors 20, 21 are taken to comparators 23, 24 so that if the output of sensor 20 drops below a predetermined level caused by a widening of the jet the comparator 23 gives an output to a relay 25 to actuate the safety shutter 10.

Similarly if the output of sensor 21 rises due to the jet narrowing, comparator 24 gives an output to a further relay 26 again actuating the safety shutter 10. Thus an abnormal output from either sensor causes closure of the shutter 10. Should the output of a sensor return to normal after closure of the shutter 10 a delay circuit 27 is provided so that the shutter 10 is only opened after a predetermined delay. The comparators, delay circuit and relays are all conventional in design.

Naturally, by the addition of further pairs of sensors, comparators and relays, checks can be made in every dimension of the jet. In such a case a gate circuit of well known design would be provided so that abnormal reading from any single sensor would actuate closure of the shutter 10. The second embodiment, illustrated in FIG. 2, is identical to the embodiment of FIG. 1 save

that the pipe 2 is bent through a right-angle so that the jet extends approximately horizontally. In this embodiment gravity affects the position of the jet if the flow rate varies appreciably and the jet must be fed by a system giving an approximately constant flow rate such as a constant head tank.

FIG. 3 shows a third embodiment incorporating a second system by means of which the x-ray detector 6 can be protected. In this embodiment the detector 6 is

mounted on a lever 30 pivoted at 31 and coupled to a double-acting hydraulic ram 32. In this embodiment integers similar to those of the embodiment of FIGS. 1 and 2 have the same reference numerals. Thus should the rate of flow of the jet fall below a particular value or the dimensions of the jet vary outside predetermined limits, the ram 32 is actuated to swing the detector 6 away from the circuitry of the jet and will not return the detector to its operative position until all the readings from the various sensors have returned to normal for a predetermined period.

In all the embodiments the jet of fluid 1 after passing the x-ray system 4 falls into a jet trap 11 which is arranged to prevent back-splashing of the x-ray system. The fact that the system of FIG. 1 employs delivery of the fluid has the advantage that the position of the jet is not affected by gravity and adequate positional stability can be achieved by feeding the jet directly from a pump giving relatively smooth delivery.

Although the shape of the orifice has been described as an elongated ellipse in cross-section, the actual shape is not critical provided there is a smooth transition from the round section of the pipe 2 to the orifice and the absence of scratches and other defects in the internal surface of the orifice.

The systems described may be used for the analysis of flowing liquids, liquid/solid, gas/solid, gas/liquid and gaseous systems. In a typical system for analysing the contents of a slurry of density about 1.2, a clearly defined jet can be obtained by arranging the slurry to have a flow rate in the range of 1500 to 3000 liters per hour through an elliptical orifice having axes of 1 and 3.5cm. Naturally the flow rate and the size and shape of the orifice can vary widely in accordance with the substances being analysed.

Although the system has been described with particular reference to x-ray fluorescence, it has possible applications in analysis by emission spectrography, by infra-red absorption, by diffuse reflection or by x-ray absorption.

I claim:

1. Apparatus for the analysis of a parameter of a moving fluid comprising means for passing said fluid through an orifice shaped to provide a fluid jet of defined dimensions; analyzing means comprising a detector of electromagnetic radiation, said detector being positioned in non-contacting proximity to said jet adjacent the orifice for receiving radiation travelling from said jet to produce a signal varying as a function of said parameter of said fluid; flow sensor means mounted adjacent said orifice for measuring the rate of flow of said fluid through said orifice; and means connected to said flow sensor means and operative to protect said detector should the rate of flow of said fluid fall below a predetermined value as indicated by said flow sensor means.

2. Apparatus as claimed in claim 1, and including a light source for illuminating at least a portion of said jet, photo-sensitive means positioned to receive light from said light source, and comparator means operative on variation of the output of said photo-sensitive means caused by variation in the radial dimensions of said jet to actuate said means for protecting said detector.

3. Apparatus as claimed in claim 2 wherein said photo-sensitive means comprise a pair of photo-sensitive detectors each connected to an individual comparator, one of said photo-sensitive detectors being so po-

sitioned that said jet will obscure it from said light source when the jet has the requisite dimensions and the other photo-sensitive detector being positioned so that it is illuminated by said light source when said jet has the requisite dimensions.

4. Apparatus as claimed in claim 1 wherein said means for protecting said detector comprises a shutter mounted for movement adjacent said jet from a withdrawn position to a protect position between said jet and said detector and actuating means operable on receipt of a signal from said flow rate sensor to cause said shutter to move from said withdrawn to said protect position.

5. Apparatus as claimed in claim 1 wherein said detector is an x-ray detector and said analysing means further comprises an x-ray source disposed for irradiating said jet to excite fluorescent x-rays which will be received by said detector.

6. Apparatus for the analysis of a parameter of a moving fluid comprising means for passing said fluid through an orifice shaped to provide a fluid jet of defined dimensions; analyzing means comprising a detector of electromagnetic radiation, said detector being positioned in non-contact proximity to said jet adjacent the orifice for receiving radiation travelling from said jet to produce a signal varying as a function of said parameter of said fluid; flow sensor means mounted adjacent said orifice for measuring the rate of flow of said fluid through said orifice; a light source for illuminating at least a portion of said jet; photosensitive detector means arranged to receive light from said light source in such a manner that any variations in the radial dimensions of said jet greater than predetermined values causes the output of said photosensitive detector means to vary; comparator means for comparing the output of said photosensitive detector means; means operative to protect said detector from said jet; means for actuating said protective means in the event of either a fall in the flow rate of said jet detected by said flow sensor means or a variation in the radial dimensions of said jet as detected by said photosensitive detector means; means for withdrawing said protective means from said detector should the outputs of said flow sensor means and said photosensitive detector means return to within normal limits.

7. Apparatus as claimed in claim 6 and further including delay means for delaying the withdrawal of said protective means for a predetermined period after the outputs of said flow sensor means and said photosensitive detector means return to within said normal limits.

8. Apparatus as claimed in claim 6 wherein said photosensitive detector means comprise a pair of photo-sensitive detectors, one of said photosensitive detectors being so positioned that said jet will obscure it from said light source when the jet has the requisite dimensions and the other photosensitive detector being positioned so that it is illuminated by said light source when said jet has the requisite dimensions.

9. Apparatus as claimed in claim 6 wherein said means for protecting said detector comprises a shutter and actuating means operable on receipt of a signal either from said flow rate sensor or said photosensitive detector means to interpose said shutter between said jet and said detector.

10. Apparatus as claimed in claim 6 wherein said detector is an x-ray detector and said analysing means further comprise an x-ray source disposed for irradiating said jet to excite fluorescent x-rays which will be re-

3,925,661
